UNITED STATES PATENT OFFICE.

PAUL STEIFF, OF GIENGEN-ON-THE-BRENZ, GERMANY, ASSIGNOR TO MARGARETE STEIFF, INC., OF NEW YORK, N. Y., A CORPORATION OF NEW YORK.

DESIGN FOR A STUFFED TOY ANIMAL OR SIMILAR ARTICLE OF MANUFACTURE.

Application filed October 26, 1928. Serial No. 28,658. Term of patent 7 years.

To all whom it may concern:

Be it known that I, PAUL STEIFF, a citizen of Wuerttemberg, Germany, residing at Kirze-Str. 1, Giengen a. Brenz, Germany, have invented a new, original, and ornamental Design for a Stuffed Toy Animal or Similar Article of Manufacture, of which the following is a specification, reference being had to the accompanying drawing, forming a part thereof, and showing a perspective face view of the stuffed toy animal embodying my design.

I claim:

The ornamental design for a stuffed toy animal, or similar article of manufacture, substantially as shown.

PAUL STEIFF.
